DELCO-REMY CORPORATION, OF ANDERSON, INDIANA, A CORPORATION OF DELA-
WARE

IGNITION SYSTEM

Application filed March 6, 1930. Serial No. 433,618.

This invention pertains to ignition systems and has for an object to provide an ignition distributor adaptable to high speed operation on multi-cylinder engines.

5 One object of this invention is to provide adequate and positive lubricating means for the various working parts of the timer-distributor unit.

A further object of this invention is to 10 provide an ignition device of the class described that will be highly efficient and can be produced at a minimum of cost.

Another object of the instant invention is 15 to provide means for adequately lubricating the movable parts of said structure.

A particular object of this invention is to provide means for lubricating the speed responsive means of the automatic spark advance.

20 A further object of this invention is to provide an oiling system for speed controlled timing mechanisms, whereby the active life of the structure may be prolonged.

Further objects and advantages of the 25 present invention will be apparent from the following description, reference being had to the accompanying drawings wherein a preferred embodiment of one form of the present invention is clearly shown.

30 In the drawings:

Fig. 1 is a vertical section through an ignition device of the class described substantially as indicated by line and arrows 1—1 of Fig. 2.

35 Fig. 2 is a plan view of the circuit breaker mechanism with the distributor cap and rotor removed.

Fig. 3 is a plan view of the speed responsive mechanism showing in detail one application of our invention, it being a view substantially as indicated by the line and arrows 3—3 of Fig. 1.

40 Fig. 4 is an enlarged sectional view of the cam carrying assembly, illustrating in detail, a part of the improvement contributing to this invention.

Fig. 5 is a plan view similar to Fig. 3, of a modification of our invention substantially as indicated by the arrow 5 in Fig. 6.

50 Fig. 6 is a vertical sectional view of a modi-

fication of our invention substantially as indicated by the line and arrows 6—6 of Fig. 5.

With particular reference to the drawings, 55 20 refers to a cup member housing a governor mechanism or speed responsive means 30 and that differentially connects a drive shaft 40 with a cam carrying shaft 45 as will presently appear. The governor cup 20 is formed with a shank 21 that provides a sleeve supporting a bearing 22 for the drive shaft 60 40. The shank 21 is provided with a bore to receive the bearing 22 and leads out from chamber 23 in the base of the cup 20. About the shank 21 is a clamp bracket or actuating arm 24 having the apertured ear 25 for connection to the manual control. 65

The chamber 23 is covered by a plate 26 and secured in tight relation with the bottom of the cup 20 by rivets 27, which coincidentally aid in securing the actuating arm 24 to the 70 cup 20. Through a lateral wall of the cup 20 and opening into the chamber 23, a grease gun fitting 28 is provided so that hard lubricant may be forced into the chamber 23 under pressure. It will be noted from reference to Fig. 1 that the bearing 22 in fact extends through the lubricant pressure chamber 75 23 and is provided with apertures 29 which give access for lubricant in the chamber 23 to the surface of the shaft 40. Throughout the extent of the bearing 22, the shaft 40 is provided with an oil groove 41, which in the present instance appears as a double ellipse or reentrant curve represented by the full and dotted line. 80

85 The speed responsive means 30 comprises a weight plate 31 press fitted upon the reduced end of the shaft 40 and supports a pair of pivot posts 32 upon which are pivoted weights 33, having cam faces 34 maintained in engagement with the cam lobes 35 of a plate 36 secured to the lower end of the cam carrying shaft 45, hereinbefore referred to. Each of the arms 35 of the plate 36 supports a spring post 37 upon which is hooked one end 90 of a spring 38 anchored to the pivot post 32. These springs normally cant the weights 33 toward the axis of the speed responsive means, yet permit the weights 33 to fly outwardly 95 upon rotation by the shaft 40. 100

As earlier stated, the shaft 40 is provided with a reduction upon which is press fitted the plate 31, supporting a speed responsive mechanism as at 42, and the shaft 40 is further reduced above the plate 31 to form the pintle or stud 43 about which is placed the lower end of the cam carrying shaft 45. The cam carrying shaft provides a longitudinal bore 46 running throughout the axis of the said shaft and terminating in the lower end thereof in a recess 47 of substantial length, and of sufficient size to telescopically engage the pintle 43 of the drive shaft 40. The recess 47 being somewhat deeper than the length of the pintle 43 provides a small chamber at the end of said pintle which may act as a lubricating chamber, and the walls of this chamber are apertured as at 39 to admit of threading a wick or lubricant absorbing member 48 therethrough, the ends of said absorbing member are carried laterally and pressed over the pivot posts 32 as illustrated at 49.

In the illustrated modification of Figs. 5 and 6, the lubricant absorbing member comprises a fibrous washer 48a of felt or the like, disposed about the lower end of the shaft 45 so as to be adjacent the aperture 39 and engage the spring posts 37.

The housing integrally or otherwise, includes a second cup member 50 that has a bridge portion 51 across the bottom thereof, providing a receptacle or seat for an anti-friction bearing 52 of the usual ball and race type as illustrated in Fig. 1. This provides a bearing for the cam carrying shaft 45 heretofore described. In the bottom of the cup and just above the bridge 51, a breaker plate 53 adjustably supports a shift plate 54, upon which is adjustably mounted a circuit breaker bracket 55 and to which is pivoted a circuit breaker 56 as at 57; the lever 56 having a contact 56a cooperating with a contact 56b supported by the bracket 55, and a rubbing block 58 electrically connected to a terminal bracket 59 of the shift plate 54 by a lever urging spring 60.

In the immediate instance, the breaker mechanism is duplicated as illustrated in Fig. 2, in that another lever 56 has a pivotal support at 57 upon the bracket 55 and is electrically connected to a terminal bracket 61 of the breaker plate 53. Each of the plates 55 are adjustable about the posts 57 by loosening the clamp screws 62 and turning of the eccentric 63 in the usual manner, whereby the dwell of the contacts may be varied to suit the conditions. The shift plate 54 is capable of adjustment upon the breaker plate 53 by reason of the clamping screws 64 and the eccentric 65, by the manipulation of which the plate 54 may be pivoted about the shaft 45 and on the plate 53, due to the flange 66 having a bearing coaxial of the cam carrying shaft.

55 The bracket 59 has provision for insulat-

ingly supporting the spring 60 through a bolt 67, bushing 68 and nut 69, securing the spring to the bracket, and also offers anchoring means for a conductor 70, by which the spring 60 and thence the breaker lever 56 may be electrically connected to a terminal post 71, insulatingly supported in the wall of the housing. The terminal bracket 61 in a similar manner supports the circuit breaker spring 60 of the second assembly, and provides electrical communication from it to the terminal post 72 by an insulated conductor 73. To each of the terminal brackets 59 and 61 there is attached a clip 74, which has electrical communication with the circuit breaker lever 56 and forms one terminal 75 of a condenser 76, and that has a second terminal thereof grounded upon the casing, the breaker plate 53 being apertured at 77 for the passage of the condenser clips.

The cam carrying shaft 45 extends somewhat above the circuit breaker assembly just described, and the axial bore 46 thereof terminates in a conical counter-sink formed into an expansible member by splitting the same into a plurality of segments, as by sawing along the axis of said shaft to provide the spring tongues 78 as illustrated in Fig. 4. About the shaft 45 is an annular groove 79 within which is disposed a collar or ring 80, and a multi-lobe cam 81 fittingly engages the end of the shaft 45 about the expansible portion, the cam member having a sleeve like extension 82 carrying the dissimilar flats 83 and 84 that provide a one-way mating relation with a distributor rotor 85.

The cam 81 would be normally rotatable about the shaft 85, but is restrained from rotation thereon by means of an expanding member 86, disposed within the spring tongues 78 and carrying a screw 87 that forces the same into engagement therewith. The expanding member 86 forms a cone and is retained on the screw 87 by a spring ring 89, seated in an annular groove of the screw 87.

It will be observed from Fig. 4, that the sleeve-like extension 82 of the cam extends somewhat above the spreading member 86 and the screw 87, whereby a small receptacle or recess 88 is provided at the end of the expansible portion of the shaft 45. The screw 87 is provided throughout the threaded portion thereof with a longitudinal groove 90 that affords communication between the slits of the wedges 78 and the axial passage 46 of the shaft.

It is thus seen that lubricant admitted to the recess 88 at the end of the expansible shank of the shaft 42 provided by the sleeve 82 of the cam, will seep down through the slits between the wedges 78, thence about the threads of the screw 87 until it reaches the passage 90, from whence it will run down the bore 46 to the chamber 47, and saturate the

wicking 48 or 48a. From there the lubricant travels along the fibers of the wicking to the pivot posts 32 of the speed responsive means. In the first form illustrated, this is by way of the wicking 48 threaded through the apertures 39 of the chamber 47 and thence along the wicking 48 until the lubricant reaches the posts 32. In the modification illustrated in Figs. 5 and 6, the lubricant reaching the chamber 47 finds its way to the absorbing material 48a through the apertures 39, and thence to the posts 37. From the posts 37, the lubricant will gradually move outwardly along the convolutions of the spring 38 until it reaches the pivot posts 32, at which time lubrication thereof will be manifest. The travel of the lubricant from the chamber 47 to the pivot posts 32 is due in part, in both instances, to the centrifugal force exerted by the rapidly rotating governor mechanism, as well as the absorption capacity of the members 48 and 48a.

Of course not all of the lubricant that reaches the chamber 47 will pass out by way of wicking 48, but sufficient thereof will be so communicated to the posts to reduce the frictional engagement of the weights therewith. The remaining portion of the lubricant that reaches the chamber 47 will tend to lubricate the surfaces of the shafts 40 and 45 at their common juncture, thus tending to reduce the frictional resistance offered to the speed responsive means in its differential coupling of the two shafts.

The extension 82 of the cam block forms driving engagement for the distributor rotor 85 earlier referred to, and this rotor moldably supports the contactor segments 92 cooperably engageable with distributor terminals 93 moldably secured within a distributor cap 94. The cap 94 likewise moldably secures a contact ring 95, and an axial terminal post 96 that make contacting engagement with the segments 92 through the brush members 97 and 98 respectively. The distributor cap has provision for making electrical engagement with insulated leads through the pointed pins 99 that are forced to pierce the insulation and engage the conductor thereof by the compression members 100 of an auxiliary cap 101 and spacer 102 that are secured to the cap 94 in any preferred manner. The caps 94 and 101 have cooperating provisions with the spacer member 102 by way of the lateral corrugated apertures 103 for engaging the insulation of the conductors and holding them in firm engagement so that the electrical connections of the conductors with the pins 99 may not readily be disturbed.

The distributor cap assembly may be secured to the timer housing in any preferred manner as by means of clamp springs 104, hinged to a bracket 105 mounted upon the cup 50. The cup 50 also supports an oil receptacle 106 having a spring cap 107 and

that empties into a trough 108 secured to the breaker plate through a clip 109 and screw 110, the trough emptying into the anti-friction bearing 52 through an aperture 111 of the plate 53.

While the form of embodiment of the present invention as herein disclosed, constitutes a preferred form, it is to be understood that other forms might be adopted, all coming within the scope of the claims which follow.

What is claimed is as follows:

1. In an ignition device the combination comprising, a timer housing, a driven shaft and a cam shaft within the housing, speed responsive means differentially connecting the shafts, said cam shaft providing an oil reservoir, and means in communication with said reservoir, for conducting lubricant to the pivotally connected members of said speed responsive means.

2. In an ignition device of the class described, the combination comprising, a housing providing a bearing for a drive shaft, a cam shaft supported within said housing and differentially connected with said drive shaft by speed responsive means, a lubricant conveying channel in said cam shaft having communication with said differential connection, and means conveying lubricant from said differential connection to movable parts of said speed responsive means.

3. In an ignition distributor, the combination comprising, a housing supporting a drive shaft, and a cam shaft differentially joined by speed responsive means, an oil receptacle provided in the end of said shaft and a channel communicating with the juncture of said cam shaft and drive shaft, lubricant absorbing means disposed at the juncture of said shafts and leading to parts of said speed responsive means whereby oil placed in the receptacle of said cam shaft will be transported to the moving parts of said speed responsive means.

4. In an ignition device of the class described, the combination comprising, a housing, a drive shaft having a bearing therein and supporting a weight plate, speed responsive means carried by said weight plate, a cam carrying shaft journaled for rotation within said housing, and having differential connection with said drive shaft through the said speed responsive means, said cam carrying shaft providing a receptacle for lubricant and carrying a lubricant absorbing member having communication with the pivot posts of said speed responsive means, whereby lubricant when admitted to said receptacle will be transmitted to the said pivot posts.

5. In an ignition device having speed responsive means for varying the time occurrence of spark impulses, the combination comprising, a drive shaft and a cam carrying shaft, said shafts being differentially

connected by said speed responsive means, a pressure lubricating chamber having communication with said drive shaft, said cam carrying shaft providing an oil receptacle 5 and having a channel in communication with said receptacle and the juncture of said shafts, and lubricant absorbing means in the region of said juncture having communication with the pivot posts of said speed responsive means, whereby lubricant admitted to said channel and absorbing means may be transmitted to said posts.

6. In an ignition distributor the combination comprising, a drive shaft, a cam carrying shaft and speed responsive means differentially connecting the same, a housing providing bearings for both of said shafts, said housing having provision for applying lubricant under pressure to said drive shaft, 15 20 an anti-friction bearing supporting said cam carrying shaft, and means for charging said anti-friction bearing and said pressure applying means with lubricant, said cam carrying shaft providing an oil receptacle and 25 channel communicating with said differential connection, and means for conveying lubricant from said differential connection to the movable parts of said speed responsive means.

30 7. In a distributor of the class described, providing a drive shaft and a cam carrying shaft with speed responsive means connecting the same, the combination comprising, an oil receptacle at the end of said cam carrying 35 shaft, and a channel communicating with the juncture of said shafts, a wicking disposed at the juncture of said shafts and having communication with the pivot posts of said speed responsive device.

40 8. In a distributor of the class described, providing a drive shaft and a cam carrying shaft with speed responsive means connecting the same, the combination with a wicking attached to the pivot posts of said speed responsive means, and passing through said shaft connection, whereby lubricant admitted thereto will be transmitted to the said pivot post.

45 9. In a distributor of the class described, 50 providing a drive shaft and a cam carrying shaft with speed responsive means connecting the same, the combination comprising an axial bore of said cam carrying shaft telescopically engaging a portion of said drive shaft, said cam carrying shaft providing a longitudinal channel and having an oil receptacle at the end remote of said shaft engagement, a wicking disposed in said bore and communicating with parts of said speed responsive means, whereby lubricant admitted to the receptacle of said cam carrying shaft will be communicated to said pivot posts.

55 10. In an ignition distributor the combination comprising, a drive shaft, a cam car-

rying shaft and speed responsive means connecting the same, a cam carried upon said cam carrying shaft, said cam carrying shaft being expansible and supporting a slotted screw with an expanding device for adjustably securing said cam upon said cam carrying shaft, and a longitudinal bore throughout said cam carrying shaft in communication with the slot of said screw, providing a lubricant carrying channel to the juncture of 75 said shafts.

11. In an ignition distributor, the combination of a rotatable cam carrying element having an expansible shank, of a cam supported on said shaft, a member for expanding said shank and means for forcing said expanding member into said shank, said cam carrying element having an axial passage therethrough, said cam providing means extending beyond said shank and expanding means, to provide a recess at the end of said cam carrying element, said expanding member and forcing means providing passages in communication with said axial passage, whereby lubricant admitted to said cam recess may be conducted to and through said axial passage.

12. In an ignition distributor, the combination of a rotatable cam carrying element having an expansible shank, of a cam supported on said shaft, a member for expanding said shank and means for forcing said expanding member into said shank, said cam carrying element having an axial passage therethrough, said cam providing means extending beyond said shank and expanding means, to provide a recess at the end of said cam carrying element, said expanding member and forcing means providing passages in communication with said axial passage, 100 a drive shaft having a portion telescopically engaged by said cam carrying element so as to provide a recess at the juncture thereof, speed responsive means differentially drivingly connecting said shaft and cam carrying element and lubricant absorbing means connecting the pivot post of said speed responsive means with said recess, whereby lubricant admitted to said cam recess may be conducted to and through said axial passage, 110 and juncture to the lubricant absorbing means, and thence to the pivot posts of said speed responsive means.

13. In an ignition distributor, the combination comprising, a cup shaped housing supporting a drive shaft and providing means for lubricating the same under pressure, speed responsive mechanism secured to said drive shaft and providing a differential connection with a cam carrying shaft, a circuit breaker cup with breaker mechanism supported by said housing and providing an anti-friction bearing for said cam carrying shaft, means exterior of the circuit breaker housing conveying lubricant to the anti-fric- 120 125 130

tion bearing, said cam carrying shaft providing a receptacle and passages in addition to lubricant absorbing means, adapted to convey lubricant to said speed responsive means.

- 5 14. In a distributor of the class described, providing a drive shaft and a cam carrying shaft with speed responsive means connecting the same, the combination comprising an axial bore of said cam carrying shaft telescopically engaging a portion of said drive shaft, said cam carrying shaft providing a longitudinal channel and having an oil receptacle at the end remote of said shaft engagement, apertures in said cam carrying shaft communicating with said axial bore, a lubricant absorbing washer encircling said shaft juncture for transmitting lubricant from said shaft juncture to ports of said speed responsive means.
- 10 15. In a distributor of the class described, providing a drive shaft and a cam carrying shaft with speed responsive means connecting the same, the combination comprising an axial bore of said cam carrying shaft telescopically engaging a portion of said drive shaft, said cam carrying shaft providing a longitudinal channel and having an oil receptacle at the end remote of said shaft engagement, apertures in said cam carrying shaft communicating with said axial bore, a lubricant absorbing washer encircling said shaft juncture for transmitting lubricant from said shaft juncture to ports of said speed responsive means.
- 15 20. In testimony whereof we hereto affix our signatures.

JOHN T. FITZSIMMONS.

JAMES L. ARTHUR.
